Primary Examiner — Lauren R Calve*(74) Attorney, Agent, or Firm* — Cook Alex Ltd.(57) **CLAIM**

The ornamental design for a flip cap package with chamfer, as shown and described.

DESCRIPTION

FIG. 1 is a top, front perspective view of a flip cap package with chamfer according to the present design.

FIG. 2 is a bottom, right side perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is a bottom plan view thereof.

FIG. 9 is a rear elevation view of a second embodiment of a flip cap package with chamfer showing the same portions of the package as the first embodiment except for the hinge in broken lines.

FIG. 10 is a right side elevation view of the embodiment of FIG. 9; and,

FIG. 11 is a left side elevation view of the embodiment of FIG. 9.

The broken lines shown represent portions of the claim that form no part of the claimed design.

1 Claim, 6 Drawing Sheets(56)
